UNITED STATES PATENT OFFICE.

GEORGE A. WILKINS, OF PHILADELPHIA, PENNSYLVANIA.

ADJUSTABLE TELEPHONE SUPPORT AND SWITCH.

SPECIFICATION forming part of Letters Patent No. 286,518, dated October 9, 1883.

Application filed March 14, 1883. (No model.)

To all whom it may concern:

Be it known that I, GEORGE A. WILKINS, of Philadelphia, in the State of Pennsylvania, have invented a new and useful Improvement in Adjustable Telephone Supports and Switches, of which the following is a specification.

My invention consists in an improved apparatus and means for operating a switch in closing and breaking the circuit of the electric current of an open-current battery of a telephone by the adjusting movements of an adjustable telephone-support, whereby the circuit is automatically closed when the telephone is brought into position for use, and is in like manner broken when the use is suspended; and in the manner of constructing an adjustable telephone-support adapted to the attachment, operation, and convenient use of a switch or switches for said purpose; and in a convenient manner of attaching to a telephone-support both the receiving and transmitting apparatus; and in the special devices by which said apparatus is adjusted and retained in convenient positions.

Figure 1 shows my adjustable telephone-support, with the telephone apparatus attached thereto not in use, the circuit being open. It is composed of a fixed hollow standard, A, which supports laterally the other portions of the apparatus, and of a movable standard, B, which stands on its own foot and is adapted to rotate thereon, held upright by standard A, and carrying two arms, C and D, as shown. An annular tablet (of which Fig. 4 shows a plan) is fixed at the top of the hollow standard, and by means of slots and adjustable stops therein, and a pin, l, fixed in said standard B, regulates and limits the rotation of the standard B. The standard B is cylindrical in form below said table, where held by the standard A, to adapt it to be rotated in its support; but above said table it is square or otherwise angular, to adapt it to be firmly grasped by the arm C, which is fitted on it so as to slide upon it longitudinally and rotate it, as described. It may be hollow, to act as a conduit for the electrical wire.

Fig. 2 shows a longitudinal section of A, and shows my said switch and the means by which it is operated. These are the switch s, which

is a metal pin-plate or bolt fixed into the standard B near its foot, and the spring w, set and adapted to turn said standard in the required direction to open the switch. The electrical wire with which connection is to be made is placed at the opening o, Figs. 2 and 3, within reach of said switch as it is rotated, the other connection being through the standard B. A moderate pressure on the arm C turns said standard against the action of said spring, the switch is brought in contact with said electrical wire, and the circuit is closed. This position is retained by holding the ear of the operator against the receiver, or by the hand, on the removal of which the spring operates to return the standard to its first position and to throw the switch out of circuit. A stop in the table t may be used to keep the circuit closed when desired. The arm C, Fig. 1, which is square, (or otherwise angular in its transverse section,) carries the receiving-telephone, and an arm, D, which is cylindrical and movable on it longitudinally, carries the transmitter. The latter may be swung on its said carrying-arm into any desired angular position relative to the vertical plane, and into any desired position relative to the receiver, on either side thereof, by swinging its said carrying-arm on the swivel-joint k, and by sliding said arm on the arm C. When not in use, the arm D is directly under and in line with the arm C, and both arms, with all their attachments, are carried away from the operator to their first position by the action of the spring w.

Fig. 5 is a transverse section of the holder h, by which the receiver is attached to its carrying-arm C. It is made in two parts, one of which, x, fits and slides upon the arm C, but is cylindrical in form on its outside. The other part, y, fits around a portion of x, like a jacket, and turns thereon. These movements of said holder and its parts regulate the position of the receiver on its carrying-arm.

Fig. 3 is a plan of the base of standard A in section, showing the switch s out of circuit. A similar device for operating a switch for the same purpose might be applied at joint k, Fig. 1, or on holder h.

Fig. 6 shows the arm C constructed in two parts, which shut together like a telescope, for

the purpose of regulating its length. It may be so made as to double back by means of the folding-joint *f*, Fig. 1.

Fig. 7 shows my said apparatus held by brackets *m n*, fixed in a wall or like support, in lieu of the fixed hollow standard, and shows the manner of adapting the table *t* and spring *w* for use in such position. The switch *s* may then be conveniently placed at the table *t*. It shows also a portable writing-table, *P*, attached to the movable standard *B*, so that it can be adjusted to a standing or sitting position of the operator and folded against the wall.

The purposes of my invention are to guard against unintentionally leaving the electric circuit closed—an accident of frequent occurrence—and to provide a complete and compact apparatus for receiving and transmitting telephonic communications, which may be used on any desk or table in ordinary and constant use, without materially encumbering it or incommoding the operator, and which will enable him to attend to his telephone without leaving his usual position.

I am aware that a telephone support is in use having an arm carrying the receiver and another the transmitter, both attached to the same standard. I do not claim, broadly, the use of two arms for such purpose on one support.

I claim as my invention—
1. In telephonic apparatus, the rotating

standard *B* and the arms *C* and *D* of a telephone-support, and the spring *w*, in combination, as described, with a transmitter and a receiver, and with a switch which is operated by the adjusting movement of said standard and arms, as described, all for the purpose and in the manner described. 35

2. In combination with the arm of a telephone-support and a receiver, the receiver-holder *h*, having the part *x*, fitted to said arm and movable longitudinally thereon, and the part *y*, fitted around and movable circumferentially on said part *x*, as shown and described, for the purpose set forth. 45

3. In combination, as described, the standard *B*, switch *s*, and arm *C* in a telephone-support, with a receiver and the wires thereof, for the purpose set forth.

4. In combination with a rotating standard of a telephone-support and the receiving apparatus, a switch and a spring, operating as described, the table *t*, and pin *l*, as described and shown, and for the purpose set forth. 50

In witness whereof I have signed my name to this specification in the presence of two witnesses. 55

GEO. A. WILKINS.
